[54] APPARATUS FOR BRUSHING AND POLISHING
ZIPPER CHAIN
1 Claim, 19 Drawing Figs.

[52] U.S. Cl. 15/21 D, 29/207.5

ABSTRACT: A brushing and polishing assembly for use in the manufacture of zipper chain. The assembly includes a body having a chain guide path and a number of brushing members disposed over the path to brush and polish exposed surfaces of the chain as it passes through the assembly.

APPARATUS FOR BRUSHING AND POLISHING ZIPPER CHAIN

This is a division of application Ser. No. 637,518, filed May 10, 1967 and now U.S. Pat. No. 3,482,301 of Dec. 9, 1969.

This invention relates to machines for forming separable fasteners or zipper chains from flat wire and in particular to a machine which includes apparatus for performing all the operations necessary to provide a finished product, i.e. a formed, sized and polished zipper chain.

In Canadian Pat. No. 661,442 of Apr. 6, 1963 there is provided a zipper machine that was substantially simplified in nature compared to those at that time known to the trade. Notwithstanding the fact that the fastener element of each zipper chain is extremely small in nature, the older forming machines were extremely large in size and relatively bulky with the result that substantial floor area was taken up in zipper-making factories. The invention of the above-mentioned Canadian patent provided substantial improvement of such machines in producing a device that was quite small and extremely fast in production. The wire and tape feeds to the machine were automatic and the device produced a zipper chain in a high footage to time ratio. However, after the chain was made, i.e. the tape and elements were secured together, the chain had to be sized and brushed or polished in separate operations.

The present invention provides, in one aspect, a zipper-chain-making device that is a further improvement over that of the above-mentioned patent. Specifically, there are improvements by way of means for brushing and cleaning or polishing each external face of the zipper after it leaves a chamfering section of the machine. In accordance with one aspect of the present invention, a brushing and polishing assembly for the manufacture of zipper chain consists of a body having a chain guide path therein; a plurality of brushing members positioned over the path adapted to brush and polish the exposed surfaces of the zipper chain, each of the brushes rotating in a counterdirection with respect to each adjacent brush; and means for applying resilient pressure on the chain elements by the brushes.

The invention is illustrated, by way of example, in the accompanying drawings in which:

FIG. 1 is a perspective view of the complete zipper-forming apparatus;

FIG. 2 is a side elevation of the upper section of the apparatus shown in FIG. 1 and illustrating in partial phantom line the drive mechanism for the various devices of the apparatus;

FIG. 3 is a side elevation view of the zipper-chain-making device shown in FIG. 2;

FIG. 4 is a sectional view taken along the lines 4-4 of FIG. 3;

FIG. 5 is a sectional view of the gapping device taken along the lines 5-5 of FIG. 3;

FIG. 6 is a section along lines 6-6 of FIG. 3;

FIG. 7 is a further side elevation of the zipper-making device, partly sectioned to show the wire feed press and backward return mechanism;

FIG. 8 is a sectional view along lines 8-8 of FIG. 3;

FIG. 9 is a sectional view of the die set assembly;

FIG. 10 is a top elevation view of the die assembly shown in FIG. 9;

FIG. 11 is a cross-sectional view of the sizing and chamfering unit shown in FIG. 2;

FIG. 12 is an end elevation of the chamfering unit shown in FIG. 11;

FIG. 13 is a top or plan view of the brushing unit showing the drive motor and bellcrank mechanism as well as the end pulley adjacent the winding spool apparatus as seen in side elevation in FIG. 2;

FIG. 14 is a further top view of the brushing mechanism shown in FIG. 13 but with the motor and protective cover removed;

FIG. 14a, 14b and 14c are sections along lines a-a, b-b, and c-c of FIG. 14;

FIG. 15 is a section taken along the lines 15-15 of FIG. 14 and disclosing the structural features of one of the brushing units; and

FIG. 16 is an end elevation of the spool and its associated winding mechanism shown in side elevation in FIG. 2.

GENERAL ASSEMBLY

Referring to FIGS. 1 and 2 of the drawings, the apparatus comprises, in its integral unit, a cabinet 1 having a control panel 2, a zipper-chain-manufacturing device 3; a sizing and chamfering device 4; a brushing and polishing device 5 and spool-winding mechanism 6. There is also included a supply roll 7 for the chain wire and a similar supply for tape can be provided adjacent the upper end of the device so that the tape may be led into the zipper-chain-making device 3 as shown. The cabinet 1 also includes a remote control panel 8 and a blower 9 for cooling the zipper-making device 3 and for collecting dust from the brushing mechanism 5.

As previously mentioned, the brushing device 5, chamfering device 4 or zipper-making device 3 can also be used independently of one another but in reference to FIGS. 1 and 2, they will be described as being interrelated to provide a full production unit.

The wire 10 is drawn from a supply source 7 upwardly through a guide tube 12 and into the zipper-making device 3 by way of a wire guide assembly 14 (FIG. 7). Simultaneously, a tape 16 is fed from a supply source (not shown) into the zipper-making device 3 by way of a tape guide 18, shown in FIG. 3. Device 3 punches the chain elements from the wire and applies them onto the bead of the tape and the tape leaves the device 3 through a tape pressure cartridge 20, shown in FIG. 4.

The chain then progresses over a guide arm 22 into the confines of the sizing and chamfering device 4 and subsequently travels around guides 24 and 26 into the brushing device 5 and is finally wound onto the spool 6 as a finished product.

In view of the tension that may be applied to both the wire before it enters the chain-making device 3 and also to the chain after it leaves the latter and progresses through the chamfering and brushing elements, means are provided to stop the machine at various stages if tension builds up to a dangerous level. It will be seen from FIG. 2 that the wire guide tube 12 is secured to an arm 28 that is pivotally mounted to the apparatus cabinet at 30. The end of this arm, adjacent the pivot 30, terminates adjacent a limit switch 32 having an actuating arm 34. If, for example, the supply spool 7 for the wire should become locked or in any way encounter sufficient friction to resist the feeding draw of the device 3, tension will be applied to the wire 10 as it passes through its guide tube 12 and, in so doing, will draw the arm 28 downwardly until such time as the upper end of the arm 28 throws the actuating arm 34 of the limit switch 32 to shut off the machine. Spring 13 applies necessary tension to tube 12 as shown.

Arm 22 is connected to a block 35 pivotally mounted at 36. Also connected to the block 35 is one end of a rod 38 which is pivotally connected at its other end to an arm 40, which in turn is pivotally mounted to the cabinet as at 42. Arm 40 is slotted as at 44 to receive one end of an actuating arm 46 on a limit switch 48. It will be appreciated that, if the tension on the chain leaving the machine 3 reaches such a degree that the arm 22 is bent downwardly beyond the position shown at 22a in phantom line, the arm 38 and arm 40 will be pivoted to such a degree that the limit switch 48 will be actuated by its arm 46 and the machine will be stopped. Limit switch 48 and the arms 38 and 22 deal with the tension applied to the chain between the chain-making apparatus 3 and the chamfering device 4.

A still further limit switch mechanism is provided between the chamfering device 4 and the brushing mechanism 5. It will be seen that chain guides 24 and 26 below the chamfering mechanism 4 are mounted on a horizontally disposed rod 50 which is mounted for pivotal movement at 52. A limit switch 54 is provided with an actuator 56 having an arm 58 which is adapted to be engaged by the horizontal rod 50. If tension on

shown in FIG. 4. The above-described brake system provides a substantial improvement over that of the previous Canadian Pat. No. 661,442 as may be seen from a review of FIG. 7 of that patent.

Another improvement of Canadian Pat. No. 661,442 that is worthy of note is the type of tape feed or drive. In the present proposal, it will be seen that the tape drive is external of the body 118, specifically on an extension of the body 118a. In the above-mentioned patent, the tape drive was internal of the frame machine which made it extremely difficult to apply regular maintenance or breakdown service. Moreover, the means of applying pressure to the tape in Canadian Pat. No. 661,442 (FIG. 5) was complicated and expensive, for example in that the arm 73 pivoted about a shaft 74 in response to pressure applied on the other end of the arm 73.

Referring again to FIG. 4, the tape feed shaft 122 is mounted for rotation in the body extension 118a by roller bearings 174 and 176. The inner or passage end of shaft 122 is knurled at 178 to apply a drawing pressure onto the tape T, as shown, and pressure is applied to the tape T by means of a pressure cartridge 180 mounted in a housing 182 and surrounded by a coil spring 184. The outer end of the cartridge 180 is connected to a cammed handle 186 whereby tension can be applied or relieved. This cartridge structure is shown in side view in FIG. 7.

The wire feed shaft 120 is mounted for rotation in the body 118 by roller bearings 188 which may be lubricated from nipples 190 as shown in FIG. 4. A desired torque resistance must also be built into the wire feed shaft to prevent a rotation faster than is required. Therefore, the shaft 120 is provided with a two-plate clutch 192 mounted between a flange 194 of the casting of the main shaft and the body 118. Pressure on the clutch is effected by the other end of the shaft 120 and specifically by a pressure nut 196 which is threadably attached to the shaft 120 as at 198. The shoulder of the pressure nut 196 has an opposing surface in a pressure washer 200 that is positioned in a countersunk region of the body 118 and intermediate the surfaces of the washer 200 and the shoulder 196 are a plurality of pressurized Belleville washers 202. It will be appreciated that adjustment of the pressure nut 196 will draw the shaft inwardly by applying pressure through the Belleville washers and therefore increasing the amount of torque necessary to rotate the shaft 120. This pressure is transferred to the outer end or driven end of the shaft 120 by means of a pressure plug 204 which acts against bearings 206 through spherical washers 208 secured in place by a capscrew 210. It will be noted that the driven end of shaft 120 is formed with a circumferential groove 212, the purpose of which will be subsequently described.

Turning now to FIG. 3, it will be seen that the drive end of the wire feed shaft 120 which includes the circumferential slot 212, is also provided with a plurality of teeth 214 whereby this shaft may be incrementally rotated through the reciprocal action of a driving blade 216 on one end of the wire feed pawl 134 that is driven by the eccentric 132 on the drive shaft 124. As previously mentioned, this driving force of the pawl 134 must overcome the tension applied to the shaft 120 by the Belleville springs 202 as well as by further spring means 218 as shown.

The tape feed pawl 138 that is driven by eccentric 136 is also provided with a blade 220 for incrementally rotating the tape feed shaft 122 by means of teeth 224 circumferentially placed on the protruding end thereof. Backlash or reversal of the shaft 122 is prevented by the blade 226 of a backfeed pawl 228 mounted on the body 118a. Pawl 228 and pawl 134 are interconnected by spring means 230.

The zipper chain may be manufactured in one continuous length or it may be desirable to manufacture the chain in lengths of say 6 inches with a 2 or 3 inch gap between each chain. The tape, of course, would remain continuous. The present apparatus provides a gapping mechanism indicated generally at 232 in FIG. 3 and shown generally in FIG. 1 and in sectional detail in FIGS. 5 and 6. The gapping device com-

prises front and rear body portions 234 and 236, respectively, secured together by capscrews 238 and this unified body is then secured to the body 118 of the zipper-making machine 3 by means of further capscrews 240.

5 Briefly, the gapping device carries a blade member 242 which cooperates with and rides in the slot 212 of the wire feed shaft 120. As shown in FIG. 2, the blade 242 is wound upon a spool 244 from whence it is fed into the gapping device 232. As shown in FIG. 5, the blade rides intermediate the front and rear bodies 234, 236 of the gapping device and rides on a key 246 extending the length of the guide. The blade is maintained in engagement with the key by a plurality of fingers 248 spaced throughout the length of the guide and these fingers are resiliently mounted on the ends of coil springs 250, as shown. Moreover, it will be seen from FIG. 6 that a plurality of setscrews 252 disposed intermediate each spring and finger 248 serves to press a ball member 254 against the side of the blade by means of a spring 256. The guide 232 is provided with a shaft 258 for operating the fingers 248 and this is accomplished by the inner ends of each spring 250 being disposed in slots 260 in the shaft as shown in FIG. 5. The outer terminal end of the shaft 258 is provided with a handle 262 connected to a collar 264 and the lower end of the collar is provided with a recess 266 adapted to receive therein the head 268 of a bolt 270, the bolt being resiliently pressed into engagement with the collar by means of a coil spring 272.

It will be apparent that, by swinging the handle 262 in an arc, the shaft 258, springs 250 and fingers 248 will be rotated so as to free the blade 242.

It will be seen from FIG. 3 that the blade 242 is provided with a low or normal elevation or height 274 and a raised portion 276. It will also be noted that the normal portion 274 corresponds in its height with the depth of the slot 212 in the wire feed 120 so that, during reciprocal action of the wire feed pawl 134 and the blade 216 thereof, the guide will be moved along one notch or tooth as is the notches on the driven end of the feed shaft 120. However, if a spacing is required between the chain elements of the zipper, for example 6-inch zippers, then a raised portion 276 will be inserted in the blade at 6-inch intervals and the length of the raised portion 276 will correspond with the distance between one zipper and the next, say 2 or 3 inches. As this portion 276 is engaged by the blade 216 of the pawl 234, blade 216 is then raised from engagement with the teeth 214 on the wire feed shaft. This therefore prevents rotation of the latter and wire is no longer fed into the device although the tape feed is constant through the action of the pawl 138 and its blade on the tape feed shaft 122. 50 After the raised portion 276 of the blade is fed through the guide and the guide outlet 242a, and the height of the blade returns to the normal portion 274, then the blade 216 will again engage the teeth 214 to institute further rotation of the wire feed shaft 120.

55 TOOL AND DIE SET

In FIG. 3, it will be seen that the body 118 of the chain-making machine has secured to its upper surface a tool seat 178 and a die set clamp 280. The die set assembly is shown in detail in FIG. 9 in section and in FIG. 10 in plan view while the tool seat may be seen in section in FIG. 7 of the drawings. As shown in FIG. 9, the die block 282 includes a bridge member 284 which extends downwardly into the confines of the device 3 as shown in pecked line in FIG. 3. This constitutes the inlet into the die block 282 of the chain wire which enters via a chain wire guide 286 shown in FIG. 7. At this point, it is controlled by a wire feed press 288 which in construction, is not unlike the tape pressure cartridge 180 shown in FIG. 5. The feed press 288 includes a pressurized wheel 290 cooperating with a knurled wheel 292. Tension may be applied or released through handle 294 which is cammed onto one end of a shaft 296 resiliently mounted by spring 298.

70 The tool seat assembly 178 includes an opening 300 by means of which a male tool may receive adjustment from a pin

302. The latter cooperates with a female punch positioned in the die set. The latter device is mounted together with a punch housing 304 which is adapted to slide in the die set guide 280 shown in FIG. 3. It will be noted in FIGS. 9 and 10 that one end of the punch housing 304 is engaged by the main eccentric 130 on the drive shaft 124. Reciprocal action of the tool housing 304 is effected by the eccentric 130 and the housing is returned and kept into engagement with the eccentric through a pair of rods 306 and their associated springs 308.

Turning now to FIG. 10, it will be seen that the tape which is drawn into the machine via a passageway 310 receives an element of the chain punched from the wire in the die set. This is effected at location 312 shown in FIG. 3. The apparatus of FIG. 10 includes left and right cams 314 and 316 which have sloped ends 318. These sloped ends act on mating surfaces of left- and right-hand jaws. The cams are held in position by suitable cam clamps 322 and, as the punch housing 304 is reciprocated backwards and forwards, the sloped surfaces 318 and 320 cause the jaws 321 to move inwardly and outwardly thereby clamping the chain element onto the tape. When the tool housing 304 is reversed through the action of the springs and rods 308 and 306, the left- and right-hand jaws of the surfaces 320 are reopened through the work of a U-shaped spring 324 shown in FIG. 9.

As will be seen from FIGS. 3 and 7, a flat, long leaf-type spring 326 serves to return the knockout in the die shoe (FIG. 7) and, as previously mentioned, this spring includes an aperture 330 through which the male member of the punch may be adjusted by pin 302. This is best shown in FIG. 7. It will also be noted from FIG. 10 that a pair of vacuum tubes 328 cooperate with the jaw members to draw away the chips formed when the element is punched from the wire and clamped onto the tape bead. The relative position of the vacuum tube 328 is coaxial. Moreover, FIGS. 9 and 10 show the means of adjusting the cam members 314 and 316 which comprises a pair of setscrews 331 that bear on sloped cooperating surfaces 332 of the outer end of the cam members 314 and 316. This provides easy access to the cams and their longitudinal adjustment in the die set.

As shown in FIG. 8, the die guide of FIG. 3 comprises a pair of plate members 334 mounted on guides 336 and held in position by capscrews 338 and Belleville washers 340. It will be appreciated that easy removal of the die block is effected by unscrewing the setscrews 338 to loosen the clamps and collar plates 334 whereby the latter may be lifted away and the die set can be removed from the body 118. This provides a substantial improvement over the older system where the complete die block had to be dismantled.

SIZING AND CHAMFERING UNIT

As shown in FIG. 1, the sizing and chamfering unit is disposed intermediate the chain-making device 3 and the brushing section 5. It works the surfaces of the chain elements of the zipper to ensure a uniform thickness thereof and also to chamfer the exposed surfaces of these elements so as to remove some of the rougher edges before the chain enters the brushing section.

As shown in FIG. 11, the chamfering device 4 comprises a body 342 having a driving section 344 and a driven section 346. It will be noted that these two sections are connected together by a relatively thin portion of the body at 348 for a purpose subsequently to be described. Each section of the body 342 receives a housing 350 and these housings are retained, for example, by capscrews 352 at the one end and are interconnected together by other capscrews 354 at the operative end.

Sections 344 and 346 rotatively mount sizing and chamfering wheels 356 and 358 respectively. Each wheel, for example 356, is mounted on a shaft 360 which, in turn, is mounted for rotation in bearings 362 in a sleeve 364 mounted in each housing. The inner end of each shaft 360 is provided with a special nut 366 having a circular rotatable portion 368. A flange 370

clamps the outer race of the bearing, each flange being secured to the adjacent face of the respective housing 350 and 352. Each flange has an annular ring 372.

Shaft 360 is provided with a driving gear 374 that meshes with and rotates a driven gear 376 as shown. Gear 374 is rotated through an overload clutch 378 by means of the sprocket 84 that is rotated by the chain shown in FIG. 1.

It will be noted that the outer ends of the housings 350 are separated by a key 382 (FIG. 12). This key can be replaced by one of greater size or the key, as shown, can be ground down so as to bring the chamfering and sizing wheels 356, 358 closer together. This action is made possible through the flexibility of the body 342 of the device by way of the resilience in between the sections 344 and 346 by means of the thin interconnecting portion 348. The key can be ground away and the housings can be retightened by means of the capscrew 354. In addition, if there is any backlash or play that has developed between the gears 374 and 376, this may be compensated for by grinding and by subsequently bringing those ends of the housings 350 closer together with a further setscrew 384 as shown in FIG. 11. The space intermediate the aligned edges of the flanges 350 is taken up by a belt 386.

Each wheel 356 and 358 is provided with a series of circumferentially spaced grooves 388 providing therebetween each groove a raised portion 390. During the sizing and chamfering operation, the grooves 388 receive the elements of the zipper chain while the raised portions 390 fall intermediate the elements of the chain. As previously mentioned, through the provision of the key 382, as shown in FIG. 12, the size or thickness of the chain can be compensated for as can the distance between the elements by replacing wheels 356, 358 with those having either a greater or smaller number of grooves on its circumferential surface.

When running spaced zipper chain, that is chain that has the elements spaced apart in, for example, 6-inch or 9-inch sections through the provision of the guide blade shown in FIG. 3, there is a danger that when the spaced sections reach the chamfering members, the elements would not always fall in their proper position with respect to the peaks and grooves of the chamfering wheels. In other words, after one section of the chain is run through, there might be a space of say 2 inches to 3 inches, then the next element of the next section would enter the space between the wheels 356 and 358. However, the position of the first element on this section might not coincide properly with the grooves 388 of the wheels 356, 358 and at least the first element of the section could be ruined before its proper position would be found by the natural positioning of the chain.

In order to prevent this misalignment and to ensure that the elements always are properly engaged, the chamfering member includes an aligner generally indicated at 392 in FIG. 12. This aligner, as shown in FIG. 11, comprises a circumferential member 394 mounted for rotation on the shaft 360 by means of a bearing 396. The aligner supports a pawl hanger 398 which, in turn, includes a pawl 400 having a spring 402 which ensures the engagement of the pawl with the grooves 388 of its wheel 356. The aligner 394 is resiliently mounted for rotation about the shaft 360 by means of a spring 404 connected at one end to a hanger 406 and, at the other end, to a pin 408.

When a piece of chain tape without elements is running through the chamfering device 4, the pawl and hanger will be in the position shown in FIG. 12. However, as the next section of chain arrives, the first element thereof will catch on the hanger 398 and, due to the fact that the pawl 400 is engaging the groove 388, will pull member 394 around so that the first element will automatically engage a proper groove and peak 388 and 390. The pawl hanger will remain in an advanced position with the pawl 400 being slipped over the grooves and peaks of the wheel 356 until such time as another space enters the area between the chamfering wheels whereby the pawl hanger will be released and the spring 404 will return the pawl and its hanger to the position shown in FIG. 12.

BRUSHING ASSEMBLY

The brushing assembly is shown in FIGS. 13 through 15 of the drawings. The brushing assembly 5 includes a tension pulley 410, the main brush housing 412 and a driven pulley 414 at the exit end of the housing. The path of the zipper chain through the housing is indicated by the arrows 416 at the end thereof. Housing 412 encloses a plurality of brushes driven by a motor 418 through pulleys 420 and 422, the latter being driven by the former by a belt 424. The brushes are mounted in a drive box 426 that is oscillated continually by a bellcrank 428 and spring 430 by means of a cam 432 mounted on the pulley 108. As shown in FIG. 13, the rotation of cam 432 effects oscillation of one arm of the bellcrank 428 through a follower 434.

Tension pulley 410 comprises a pair of vulcanized rubber rollers 436, 437 through which the chain passes as indicated by the arrows 416. The tension on the chain is maintained through a spring 438 which may be released through the action of a handle 440 actuating on an eccentric shaft (not shown). Tension is also applied to the larger of the two rollers 436 by means of a shaft 442 having a tension spring 444 thereon that applies pressure to a clutch plate 446. This prevents the chain from being drawn too fast through the brushing section between the puller 410 and the driven pulley 414. The driven pulley 414 has a center shaft 448 on which is concentrically mounted a rubber roller 450 that is in contact with a similar roller 452 mounted on a sleeve shaft 454. The latter shaft is secured to an eccentric shaft 456 which is provided with a handle 458. By turning the handle downward against the tension of a spring 460, the nip 461 of the rolls 450 and 452 will be opened.

Shaft 448 is mounted for rotation in bearings 462 and at one end is provided with a thrust spring 464 and at the other end with the pulley 108, shown and described in FIG. 1. Cam member 432 is secured to pulley 108 such as by rivets 466.

The path taken by the chain through the brushing assembly is enclosed by a removable cover 468.

FIG. 14 shows the brushing assembly with the cover removed and it will be seen that the plurality of brushing members indicated generally at 470 are rotated through pulley 422 by means of gears 472, each gear being mounted on the shaft of each brush member 470. By virtue of the interengagement of each gear with the adjacent gear, each brush rotates in a countermovement with relation to the adjacent brush. The drive box 426 comprises sidewalls 474 and 476 as well as an end wall or backwall 478 and a front wall 480, all these walls being joined together by integrally cast corners.

It will be noted that the brushing members 470 are mounted for rotation at an angle with respect to the path 416 of the zipper chain. Accordingly, each brush is longer than the adjacent brush and the front wall 480 of the box 426 assumes a zigzag pattern throughout its extent.

Each brush is substantially identical with the next and FIG. 15 is a side sectional view of the second brush from the left of the drawing taken along the lines 15-15 of FIG. 14.

Referring firstly to FIG. 14, each brush member such as 470a is divided into two main sections, that lying within the confines of the walls of the box and the other section being outside the confines of the box in the area which is designated as the cleaning area.

Brush 470a consists of a first shaft 482 mounted in the walls 478 and 480 by means of bearings 484. The brushing member 470a is also provided with an outer shaft 486 mounted in a housing 488, this housing being interconnected to the wall 480 of the drive box by a resilient spring blade 490 and it will be noted from FIG. 15 that the spring blade is bent to provide a downward pressure of the brushing member onto the path 416 of the zipper chain. Shafts 482 and 486 are provided on their opposing aligned ends with shoulder grips to receive a rubber coupling 492. Outer shaft 486 is mounted in sleeve bearings 494 and the terminal end of the shaft is provided with a wire brush 496 secured thereto by a pin 498.

It will be appreciated that, due to the provision of the spring blade 490 and the resilient rubber coupling 492, the brushes 496 of the assembly 470 resiliently and flexibly engage the surfaces of the zipper chain as it passes through the mechanism. Furthermore, this particular type of mounting provides easy removal of the brushes for maintenance.

The floor or plate of the drive box 426 is also provided with two other pivotal connections 500 which, in company with the bellcrank 428, allow the pivotal movement of the complete brushing unit. This ensures that the chain receives an even brushing and that the brushes 496 themselves receive even wear across their faces. In addition, the drive motor 418 is supplied with a control means (not shown) which reverses the polarity of the motor each time the machine is stopped so that the brushes, although counterrotating, are reversed in their rotating direction each time the machine is started.

FIGS. 14a, 14b and 14c are sections taken at a-a, b-b and c-c of FIG. 14 to show the path 416 taken by the zipper chain and the means for reversing the chain so that its side and end surfaces are brushed before it is wound onto the spool 6.

In FIG. 14a it is shown that the chain enters the path 416 from the tension puller 410 with the tape of the chain beneath a tie plate 502 secured in a block 504 while the element of the chain is seated in a groove 506 of a block 508. It will also be noted that the surface of the element is disposed above the plane of both the block 508 and the plate 502. After leaving the block 508 at 416a (FIG. 14) the chain then enters that portion of the run shown in FIG. 14b in which the outer terminal end of the element of the chain is disposed slightly above the plane of two adjacent blocks 510 with the remainder of the element seated in a groove 512 formed by the blocks 510 and it will be noted that the tape extends downwardly into a further groove 514. The chain is then turned over onto its side by a plate 516 (FIG. 14) to enter the final brushing stage which is substantially a reversal of the stage shown in FIG. 14a. In FIG. 14c it is seen that a groove 506a retains the element of the zipper chain with one side surface thereof extending above the plane of a block 508a and a tie plate 502a. After the chain leaves the section shown in FIG. 14c it then proceeds into the nip of the rollers 450 and 452 shown in FIG. 13 and then proceeds to the winding spool 6.

It will be appreciated that, due to the various positions taken by the zipper chain and tape during its run through the passage 416 and due also to the location of the brushing members 470, the elements of the chain will be brushed on both sides as well as the end face and, in addition, each side will be brushed both ways, i.e. on the side leading into the brushing section as well as the side leading out of the brushing section due to the fact that every second brush of the mechanism is rotating counterclockwise with respect to the preceding brush.

As shown in FIGS. 2 and 16, the winding spool is generally indicated at 6 and is mounted on one end of the cabinet of the complete apparatus. The gearbox 112 is driven by the pulley 114 through the action of a belt 115 circulated by the pulley 110. See FIG. 2. The gearbox is provided with an output pulley 518 which rotates the winding spool 6 through the wire belt 116.

Winding spool 6 comprises a shaft 520 having a pair of end plates 521, 522 and a pulley 524 driven by the belt 116. Pulley 524 is mounted for rotation in bearings 526 provided in one end of a lever arm 528.

The gearbox 112 is mounted on a plate 530, the latter having a pair of depending leg plates 532. The other end of lever arm 528 which supports the pulley 524 curves about in the manner shown in FIG. 16 and terminates in a shaft 534 rotatably mounted in the leg plates 532 in bearings 536. Integrally formed with the lever 528 on shaft 532 is a cam follower arm 538 provided on its terminal end with a follower 540. Intermediate its two ends, the follower arm 538 is provided with a spring 542 which interconnects the arm with the sideplate of the apparatus.

Gearbox 112 also includes an output shaft 544 on which is mounted a heart-shaped cam 546. Due to the integral arrangement of the follower arm 538 and lever arm 528, rotation of the cam 546 causes the follower 540 and its arm 538 to oscillate backwards and forwards and to impart the same movement to the arm 528 and pulley shaft 520. This has the effect of rocking the pulley 6 backwards and forwards to the pecked line positions to evenly wind the zipper chain as it leave the nip of the drive pulley at the end of the brushing section as shown in FIG. 2.

It will be appreciated that the described apparatus provides a complete zipper-manufacturing apparatus from the stage of wire and tape right through to the finished brushed and wound product. On the other hand, the four separate stages of the apparatus, zipper maker; chamfering device; brushing device; and spoolwinder, are all adaptable to fit on to or in company with existing zipper-making machines.

I claim:

1. In the manufacture of zipper chain, a brushing and polishing assembly comprising a body having a chain guide path therein; a plurality of brushing members positioned over said path adapted to brush and polish the exposed surfaces of said zipper chain; each said brush rotating in a counterdirection with respect to each adjacent brush; each brush comprising two sections, a first section including a shaft mounted for rotation in a drive box and a second section including a further shaft spaced from said first shaft beyond the confines of said drive box, said further shaft including the mounting of said brush thereon above said guide path; a flexible tube interconnecting the adjacent terminal ends of said first and second shafts; and a spring member interconnecting said sections and being so disposed as to apply a downward pressure of said brush onto said chain elements.
